Inventor

UNITED STATES PATENT OFFICE.

JOE DANCULOVICH, OF ELY, MINNESOTA.

RAILROAD-SPIKE.

1 108,067.

Specification of Letters Patent. Patented Aug. 18, 1914.

Application filed May 1, 1914. Serial No. 835,665.

To all whom it may concern:

Be it known that I, JOE DANCULOVICH, a subject of the Emperor of Austria-Hungary, residing at Ely, in the county of St. Louis and State of Minnesota, have invented certain new and useful Improvements in Railroad-Spikes; and I do hereby declare the following to be a full, clear, and exact description of the invention, such as will 10 enable others skilled in the art to which it appertains to make and use the same.

My invention consists of certain new and useful improvements in railroad spikes and relates particularly to that class of spikes 15 which have portions for engaging both the rail base and the under surface of the rail head.

In devices of this character, heretofore known, the portion of the spike which engages the under surface of the head of the rail, is integral with the spike proper, and when it is desired to bring this upper part of the spike into engagement with the rail, it is necessary to bend the same after the spike has been driven into place. This bending of the head engaging part by hammering causes the shank of the spike to be loosened, thereby rendering the clamping of the rail insecure. It is to obviate this defect and to provide an efficient holding means for railroad rails that the present invention has been devised.

The object of my invention, therefore, is to improve the construction of railroad spikes of the general type above referred to, whereby their durability, strength and utility are increased and to provide a simple and inexpensive device particularly adapted for employment on curves and capable of 40 effectually preventing rails from spreading.

The invention consists in the construction and novel combination and arrangement of parts hereinafter described, illustrated in the accompanying drawings and more particularly pointed out in the appended claims.

In the drawings, Figure 1 is a vertical section of a rail and tie showing my invention used in connection therewith. Fig. 2 is a top plan view showing the head of the 50 rail removed for the purpose of clearness. Fig. 3 is a perspective view of the shank and base portion of my improved spike. Fig. 4 is a perspective view of the locking or pivoted portion of the same.

55 1 designates a railway tie and 2 a rail placed therein.

My improved device comprises a main portion 1^a and a movable locking portion 10. The main portion 1^a consists of a base plate 3 having on its underside, near its inner edge, a rabbet 4 for engaging the upper surface of the rail base. Integral with the underside of the base plate 3 and preferably disposed in the center thereof, is a triangular shaped shank 5 and on the outer edge of said base plate are downwardly depending short shanks 6. These shanks form additional securing means for the spike and which will prevent the latter from loosening.

A vertically extending pin 7 having a horizontally disposed opening 8 is provided upon the upper surface of the base plate 3 and horizontal lugs 9 are placed on the sides of said base plate to facilitate the 70 withdrawal of the spike by a claw or other tool.

The movable locking portion 10 consists of a block having a vertically disposed aperture 11 which engages the pin 7 when the two parts of the spike are united. A cut away portion or rabbet 12 is provided in said block and the upper surface of the block is substantially horizontal, as shown at 13, to fit under the head of the rail. A 80 curved surface 14 extends upwardly from the bottom of the block to the horizontally disposed surface 13, on the side opposite to the rabbet 12 to engage the web of the rail.

The block is preferably provided with an 85 opening 15, which communicates with the horizontal opening 11, for the passage of a bolt 16. When the locking member is turned on the pin 7, to locking position the bolt 16 is passed through the opening 15, and the 90 opening 8 in the pin 7, to secure said block on said base. A cotter pin 17 is passed through said bolt to retain the same in place.

An ear 18, having an opening 19 for the insertion of a suitable tool, is provided on 100 the side of said block by means of which the block may be turned on its pivot.

In the operation of my device, the shanks of the part 1^a are first driven into the tie and the rabbet 4 brought into contact with the upper surface of the base of the rail, the contact with the rail being maintained by the short shanks 6, which prevent the spike from moving laterally and the consequent spreading of the rails. When the shank of 105 the part 1^a has been driven into place, the part 10 is placed on the pin 11 with its rab-

bet 12 toward the rail head. A tool is then inserted in the aperture 19 and the part 10 turned on its pivot to bring the surface 13 into contact with the underside of the head 5 of the rail and the upper portion of its curved surface 14 into engagement with the rail web. The pin 16 is then inserted through the openings 15 and 8 which securely locks the two parts of the spike in 10 operative position.

The device has the following meritorious features: The spike which is simple and comparatively inexpensive in construction, is adapted particularly for use on curves 15 and switches, where the rails are subjected to a maximum longitudinal and lateral pressure, and it will effectually prevent the rails from spreading and getting out of alignment.

20 It will be appreciated by those skilled in the art, that the device shown is merely typical and may be modified or varied in many ways without departing from the spirit or sacrificing any of the advantages 25 of this invention as set forth in the claims annexed.

What I claim and desire to secure by Letters Patent is:—

1. A spike comprising a base having 30 means for securing the same to a railway tie, and a locking member pivotally mounted on the top of said base, and adapted to engage the under surface of the head of the rail.

35 2. A spike comprising a base having a shank for engaging the tie, a pin provided upon the top of said base, and a locking member pivotally mounted on said pin, and adapted to engage the under surface of the 40 head of the rail.

3. A spike comprising a base having a shank for engaging the tie, shorter shanks for also engaging the tie, and a locking member pivotally mounted on the top of

said base, and adapted to engage the under 45 surface of the head of the rail.

4. A spike comprising a base having a shank for engaging the tie, a pin provided upon the upper surface of said base, and a locking block mounted upon said pin, said 50 block having a high side and a low side, the locking block being adapted to be placed on said pin with its low side toward the rail and then turned to bring the high side into engagement with the head and web of the 55 rail.

5. A spike comprising a base having a shank for engaging the tie, a locking block pivotally mounted on said base, and projections provided on the side of said base, 60 whereby the withdrawal of said spike may be facilitated.

6. A spike comprising a base having a shank for engaging the tie, a pin provided upon said base, a locking block loosely 65 mounted on said pin, and means for locking said block upon said pin.

7. A spike comprising a base having a shank for engaging the tie, a pin provided upon said base and a locking block loosely 70 mounted on said pin and having a cut away portion on one side thereof, a curved surface on the opposite side and a horizontal surface connecting said curved surface and said cut away portion, said block being adapted to 75 be placed on said pin with its cut away side toward the rail and then turned to bring the horizontal surface into contact with the underside of the head of the rail and the upper portion of the curved surface into engagement with the rail web.

In testimony whereof I affix my signature, in the presence of two witnesses.

JOE DANCULOVICH.
